PORTABLE ROTARY SURFACE FINISHING MACHINE

Arthur C. Burleigh, Wellesley, Mass.

Application December 9, 1955, Serial No. 39,254

Term of patent 14 years

(Cl. D37—1)

FIG. 1

FIG. 2

FIG. 3

FIG. 4

Fig. 1 is a side elevation of a portable rotary surface finishing machine embodying my invention.

Fig. 2 is a top plan view of Fig. 1.

Fig. 3 is an end view looking toward the right in Fig. 1.

Fig. 4 is an end view looking toward the left in Fig. 1.
I claim:

The ornamental design for a portable rotary surface finishing machine, as shown.
